UNITED STATES PATENT OFFICE.

PETER L. MARKEY, OF CHICAGO, ILLINOIS.

NECKTIE HOLDER.

Application filed June 13, 1923. Serial No. 645,016.

To all whom it may concern:

Be it known that I, PETER L. MARKEY, a citizen of the United States, residing at Chicago, in the county of Cook and State 5 of Illinois, have invented certain new and useful Improvements in Necktie Holders, of which the following is a specification.

My invention relates to a necktie holder, and more particularly to a device which is 10 adapted to properly support a bow-tie or four-in-hand tie in position on the collar of the wearer.

One of the objects of the present invention is to provide a novel and very efficient, 15 as well as a strong frame construction for a necktie holder.

A further object of the invention is to provide a reinforcing member formed as an integral part of the frame or base and 20 bent back upon itself in such a manner as to form a shield or casing for carrying the latch bar which locks the necktie holder in various positions of adjustment.

A still further object of the device is to 25 provide means on the latch bar which will permit the operator to firmly grip the necktie holder when attaching or detaching the same from the collar button.

A still further object of the device is to 30 provide means for supporting the necktie on the holder and at the same time provide additional means for preventing the tie from slipping off the holder.

These and other objects are obtained by 35 providing a construction and arrangement of the various parts in the manner hereinafter described and particularly pointed out in the appended claims.

One embodiment of the invention is illustrated in the accompanying drawings, and 40 in these drawings,

Fig. 1 is a perspective view of a four-in-hand tie mounted on my improved necktie holder and showing the manner in which the 45 same supports the tie on the collar.

Fig. 2 is a rear elevational view of my improved necktie holder showing the four-in-hand tie mounted thereon.

Fig. 3 is a front elevational view of my 50 improved necktie holder showing the manner in which the latch bar is mounted previous to the bending of the reinforcing member back upon the main frame member for forming a casing for shielding the latch bar.

Fig. 4 is a front elevational view with the reinforcing member bent back upon the main frame and with the latch bar swung to its disengaging position.

Fig. 5 is a top plan view showing the collar in cross section and the necktie in dotted lines.

Fig. 6 is a cross sectional view taken on lines 6—6 in Fig. 4 looking in the direction of the arrows.

Fig. 7 is a cross sectional view taken on line 7—7 in Fig. 4 looking in the direction of the arrows, and

Fig. 8 is a perspective view showing the manner in which my improved necktie 70 holder may support a bow-tie in its proper position on the collar as well as a four-in-hand tie.

In carrying out my invention I employ a main frame or base member 10, preferably 75 made of one piece of flexible metallic material having outwardly and upwardly arched or curved arms 11 and curved in a vertical plane as shown in Fig. 5 to conform to the curvature of the collar. The frame 80 or base member 10 as cut out of the original material is provided with a reinforcing member 12 which is positioned opposite the base or frame member 10. The base 10 and reinforcing member 12 are provided with a vertically extending slot 13. The reinforcing member 12 is provided with a relatively small slotted aperture 14 for the purpose hereinafter set forth. The base member 85 10, at its lower end thereof is provided with, or has formed as an integral part thereof, a riveting or spacing member 15. The spacing member 15 is provided with an oppositely disposed shoulder 16 and a relatively reduced portion 17.

In connection with my improved frame construction for a necktie holder the reinforcing member 12 is folded back upon the base frame member 10 in such a manner as to be spaced from the base member in order 90 to form a casing or shield for the latch bar hereinafter described. When the reinforcing member is bent back as shown at 18 in Figs. 4 and 7, the reduced portion 17 of the spacing member 15 is inserted in the 100 aperture 14 of the reinforcing member 12 with the inner side of the reinforcing member 12 resting on the shoulders 16 of the spacing member, in which position the head 105 of the spacing member is riveted as shown 110

at 19 and thereby securing the reinforcing member 12 in place with the base member 10. Previous to securing this reinforcing member 12 to the base member 10, it is, 5 of course, necessary to position a latch bar 20 having an aperture 21 at its lower end thereof therebetween, with this aperture in pivotal engagement with the spacing member 15, as clearly shown in Figs. 3 and 5. 10 The latch bar 20 is provided with a plurality of notches 22 which are adapted to engage the shank portion 23 of the collar button 24 so that the necktie holder may be adjusted vertically in different positions of 15 adjustment with respect to the collar button. The latch bar 20 is normally actuated to swing across the slot 13 in its casing between the base member 10 and the reinforcing member 12 by a spring 25 pivotally 20 mounted on a projection 26 secured to or formed as an integral part of one of the arms 11. The lower end 27 of the spring 25 engages an upwardly curved portion 28 of the latch bar 20 in a manner to actuate it about its pivot to cause the same to lock the necktie holder on the collar button. The upper end 29 of the spring 25 is adapted to engage the underside of the bent portion 25 as clearly shown in Fig. 4. The latch 30 bar 20 is provided with an offset projecting stop 30 formed as an integral part of the curved portion 28 and is adapted to engage one side of the base member 10 as the latch bar 20 is actuated about its pivot on the 35 spacing member 15 to disengage the necktie holder from the collar button. Or, in other words, when the latch bar 20 is actuated to the position shown in Fig. 4 the stop portion 30 engages the edge of the base 10 40 in a manner to limit the pivotal movement of the latch bar. In order to assist the operator in positively gripping the necktie holder and preventing the same from slipping from the operator's hand when the 45 holder is being detached from the collar button, I have provided a laterally extending lug 31 formed on the latch bar 20 substantially opposite the stop 30. From this construction it will be seen that as the 50 thumb of the operator is pressed against the stop portion 30 in the operation of disengaging the necktie holder from the collar button of the collar, the latch bar 20 is actuated about its pivot and then the 55 forefinger of the operator engages the lug or projection 31 of the latch bar and thereby maintains the latch bar, with the forefinger, disengaged from the collar button as the necktie holder is drawn downwardly, sliding 60 the collar button through the open slot 13 in said holder.

In the operation of detaching or attaching the necktie holder to the collar button, it will be seen that the lug 31 of the latch bar 20 is very essential to the successful

operation of detaching the necktie holder from the collar button for the reason that the normal pulling down of the necktie holder with the thumb engaging the stop member 30 of the latch bar 20 would cause 70 the latch bar, if there were no lug 31, to swing into locking position and lock the holder on the button, but by reason of this lug or projection 31 the latch bar 20 is positively maintained in its unlocked position by pulling down on this lug during the withdrawal of the necktie holder from the collar button.

The curved or arched arms 11 are provided with, at their outer ends, upwardly turned prongs 32. These prongs 32 are so connected with the arms 11 as to form sockets 33 therebetween. These sockets normally maintain or support the tie in position on the holder, as clearly shown in Fig. 2. 80 Positioned intermediate the prongs 32 and the base 10 and extending downwardly from the arms 11 are two piercing members 34. These piercing members are adapted to engage the tie as clearly shown in Figs. 2 85 and 8 in a manner to prevent the displacement of the tie from its proper position on the holder. 90

From the construction of the necktie holder above described, it will be seen that I 95 have provided a very efficient as well as strong frame construction of a necktie holder and also utilize the strengthening means for providing a casing which entirely incases the latch bar mechanism together with the 100 spring and thereby prevents or shields this mechanism from outside interference, which would be liable to affect its efficient operation.

In connection with this improved necktie holder, it will, of course, be understood that the bow-tie as shown in Fig. 8 is just as capable of being supported on this 105 holder as is the four-in-hand tie shown in Fig. 2.

While in the above specification, I have described one embodiment which my invention may assume in practice, it will of course be understood that the same is capable of modification and that modification may be employed without departing from the spirit and scope of the invention as expressed in 115 the following claims.

What I claim as my invention and desire to secure by Letters Patent is:

1. A necktie holder comprising a base, 120 arms extending outwardly from said base, prongs connected to the outer ends of said arms, a reinforcing member formed integrally with said base and a slot extending in said base and reinforcing member for detachably securing the necktie holder on a collar button.

2. A necktie holder comprising a base, 125 arms extending outwardly from said base,

prongs connected to the outer ends of said arms, a reinforcing member formed integrally with said base, a latch bar mounted on said base, and means for shielding said 5 latch bar between said base and reinforcing member.

3. A necktie holder comprising a frame, means carried by said frame for detachably securing the necktie holder to a collar button, and means formed as an integral part 10 of said base for reinforcing said base and shielding said first named means.

4. A necktie holder comprising a frame, a latch bar carried by said frame for detachably securing the necktie holder to a collar 15 button, and means formed as an integral part of said base for reinforcing said base and shielding said first named means.

5. A necktie holder comprising a frame, 20 a latch bar pivotally mounted on said frame, a stop carried by said latch bar and engageable with said frame for limiting the movement of said latch bar, and means carried by said latch bar opposite said stop for permitting the operator to firmly grip said necktie 25 holder.

6. A necktie holder comprising a base, arms extending outwardly from said base, prongs extending upwardly from said arms, 30 and means positioned between said prongs

and base for retaining a tie on said necktie holder.

7. A necktie holder comprising a base, arms extending outwardly from said base, prongs extending upwardly from said arms, 35 and piercing means positioned between said prongs and base for retaining a tie on said necktie holder.

8. A necktie holder comprising a base, arms extending outwardly from said base, 40 prongs extending upwardly from said arm for supporting a necktie thereon, and downwardly projecting piercing means carried by said arms for retaining a necktie on said prongs.

9. A necktie holder comprising a frame, means for supporting a tie thereon, a spring actuated latch bar carried by said base, and means formed as an integral part of said 45 frame for housing said spring actuated latch bar.

10. A necktie holder comprising a frame, means for supporting a necktie thereon, a latch bar carried thereby, and a member spaced from said frame for reinforcing said 50 frame and for housing said latch bar.

In testimony whereof I have signed my name to this specification on this 25th day of May, A. D. 1923.

PETER L. MARKEY.
